UNITED STATES PATENT OFFICE.

JOSIAH HULLAH, OF AMBOY, ILLINOIS.

MEANS FOR CONNECTING STATIONARY MACHINES TO PORTABLE ENGINES.

SPECIFICATION forming part of Letters Patent No. 496,568, dated May 2, 1893.

Application filed August 11, 1892. Serial No. 442,756. (No model.)

To all whom it may concern:

Be it known that I, JOSIAH HULLAH, a citizen of the United States, residing at Amboy, in the county of Lee and State of Illinois, have 5 invented certain new and useful Improvements in Means for Connecting Stationary Machines to Portable Engines; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to an improvement in means for connecting stationary machines such as thrashing machines, corn shellers, &c., to portable engines, my object being to so arrange the pulley that the motive power may 20 be placed in any convenient position irrespective of the location of the machine.

To this end my invention consists of certain improvements of construction and arrangements of parts which will be more fully 25 described hereinafter and pointed out in the claim.

Referring to the accompanying drawings which represent my invention applied to a corn sheller: Figure 1 is a front view in elevation; Fig. 2, a side view in elevation. Fig. 3 is a plan view of my complete invention, showing the method of arranging the same.

The reference letter *a* represents the frame of an ordinary corn sheller to which my improvements are applied by means of the brackets *b* and *b'* projecting laterally from the side of the machine, and having the bearing boxes *c* and *c* formed in their ends. Journaled in these boxes is a vertical shaft *d*, 35 having the flanged pulley *d'* fixed thereto. This forms the driving pulley of the machine.

Journalized in boxes *e* and *e'* is a vertical shaft *f* to whose upper end is fixed a beveled gear wheel *g*. This gear wheel meshes with a similar gear *g'* keyed to the main shaft *g''* of the machine. The lower end of the shaft *f* has fixed thereto a smaller beveled gear *h*, which in turn meshes with a second beveled gear *h'* keyed to the tumbler-rod shaft *f'*.

Mounted on shaft *f*, between its bearings *e* 50 and *e'*, is a spur gear wheel *i*. This gear meshes with a pinion *j* keyed to the pulley shaft *d*. By means of these gears the shaft *f* is given a continuous rotary motion which imparts a similar motion to the shafts *f'* and *g''*. The belt from the pulley *r* attached to the engine or motive power employed, passes 55 over the pulley *d'* having a vertical axis and is prevented from slipping down by means of the belt-support *k*. This latter arrangement 60 will now be described.

Mounted on a horizontal shaft *m* is a flanged pulley *l*. The shaft is journaled in the upper end of the leg *n*. Hinged to this leg at *o* is a second leg or support *p*, which 65 is so constructed that it may be made to swing toward or from the leg *n*. The lower ends of each of the legs *n* and *p*, are provided with metallic spurs or points *q*, which are adapted to engage the ground or floor upon 70 which the support may be resting. By means of this arrangement the power belt is prevented from slipping down off the pulley *e*, and becoming entangled with the working parts of the machine.

It is obvious that by this manner of arranging the power pulley, the source of power may be placed in any position within the circumference of the semi-circle which lies around one side of the machine. Heretofore 80 this could not be accomplished by reason of the pulley being located horizontally. This defect causes much trouble and annoyance in the arrangement of the machines, and is overcome by my improvement.

Having thus described my invention, what I claim as new, and desire to secure by Letters Patent, is—

The combination of a pulley having a vertical axis located on a stationary machine, a 90 pulley having a horizontal axis on a movable engine or other source of power from which pulley power is derived and the pulley having a vertical axis driven, a belt connecting said pulleys, and a portable belt support having a pulley having a horizontal axis arranged between the two pulleys to change the edgewise disposition of the belt from a 95

horizontal to a vertical position, whereby the power pulley and machine to which it is attached may be placed in any position, irrespective of the position of the pulley having 5 a vertical axis, within the radius of the semi-circle that the connecting belt is capable of describing, substantially as described.

In testimony whereof I affix my signature in presence of two witnesses.

JOSIAH HULLAH.
